SPRINKLER

Guadalupe Buelna, Santa Barbara, Calif., assignor to L. R. Nelson Mfg. Co., Inc., Peoria, Ill., a corporation of Illinois

Application March 1, 1939, Serial No. 259,099

10 Claims. (Cl. 299—68)

This invention relates to water sprinklers of the type employed in treating extensive lawns, gardens, and on golf courses.

More particularly the invention has to do with 5 a type of sprinkler having a slow rotary movement but wherein the device is made to have a step-by-step progress.

The main object of the invention is to furnish 10 a form of mechanism wherein a continuously rotated element driven by a nozzle stream transfers to an arm of the sprinkler distant from the axis of rotation of said sprinkler a series of blows by which to urge the same in a step by step manner for thorough wetting of the area to be treated.

15 Another object lies in providing a rapidly whirling driven member, and an arm driven thereby so mounted as to swing in a given plane and to be brought into a position during its rapid whirling where it will positively strike at regular intervals an arm of the sprinkler body lying at 20 one side of the axis of rotation of the latter thereby to urge said body forward in a step-by-step rotary movement.

Again an object is to so mount a whirling arm 25 with respect to a part of the sprinkler body that, whereas, under certain conditions it would have no effect upon said sprinkler, at a high speed of rotation due to centrifugal force will be made to strike said part of the sprinkler body and 30 thereby urge the same forward.

Further, to so arrange the named structure that the arm at each rotation or whirling action will strike the sprinkler body and thus urge it 35 forward a distance on its mounting commensurate with the blow delivered and then due to the interruption of its whirling action will automatically be released, taking up a further whirling action for succeeding blows upon the body.

Besides the objects thus noted the invention is 40 directed to certain structures to be brought out herein and to form the subject of some of the claims to follow.

45 That the invention may be thoroughly understood in all of its aspects the appended drawings are provided forming part hereof:

Figure 1 is a plan of one of the forms of 45 sprinkler involving the present invention;

Figure 2 is a side elevation of the same;

50 Figure 2a is an elevation of an arm taken on line 2a of Figure 1;

Figure 3 illustrates a driven member as seen at its under surface or that surface against which driving power is applied in the form of a water-jet;

55 Figure 4 is a sectional elevation of a slightly

modified form of device also involving the invention herein;

Figure 5 shows in perspective an arm illustrated in Figure 4;

Figure 6 is a plan of parts shown in said Figure 4;

Figure 7 shows parts illustrated in Figure 4 as viewed from the under side thereof, and

Figure 8 is a plan of a distributor plate shown in said Figure 4.

In Figure 1 the character 1 denotes a sprinkler body mounted to rotate in a horizontal plane on any suitable water supply portion 2 as is customary in devices of this type, 3 denoting any usual discharge nozzle, while 4 is a jet nozzle for a purpose to be made known herein. In this instance a disc or wheel 5 fluted at 5' is mounted on the top of the body 1 adapted to rotate, a suitable support or abutment 6 being provided therefor. In this instance, also, an arm 1' extends from the body 1 from the side thereof directly opposite the nozzle 3 in balanced relation to the end that free rotation of the body on its mounting will result, the axis of said disc or wheel 5 preferably lying between said nozzle 3 and arm 1' in preserving balance of the whole.

Arising from the center of the disc 5 is a stem 7 which may take the form of a screw acting as a shaft for the disc, and fixed in said support or abutment 6, the head of the screw serving to retain an arm 8 thereon. This arm at one end or that at said stem 7 is provided with a hole 9 much larger than the stem and said end of the arm, in the present instance, lies some distance above the top of the disc 5 upon a hub 5' of the latter, and from thence is curved downwardly, the outer portion of such arm normally resting upon said disc. Near the edge of the disc a pin 10 is erected, there being a hole 11 in the arm to receive said pin and larger than the latter, said arm being extended some distance beyond the disc where its free end will lie at the arm 1' of the sprinkler body.

In Figure 1 it will be noted that this arm on its inner side or that facing the disc is provided with a notch 12 and that, as shown, the arm 8 is free to pass therethrough. Also, that when the said arm 8 is raised as shown by broken lines it is in position to strike said arm 1'. The reason for this particular relation of the two arms will be brought out in the description of the operation of the device. At this time, however, it is to be stated that the disc 5 is intended to rotate at a high speed. Since, now, the arm 8 which is to rotate with said disc would naturally tend

to set up undue vibration in the device as a whole a counterbalance lies at the disc's edge diametrically opposite the position of said arm 8 in the form of a heavy lug 13. By the latter provision, therefore, a nice balance of the assembled rotating parts is maintained.

The issuance of a stream from the main nozzle 3, when the latter is directed away from the axis of rotation of the sprinkler, results of course, in no rotative action of the said sprinkler. However, since as the device is constituted results in a stream of water from the secondary nozzle 4 such stream will be directed upon the fluted disc-periphery setting the disc in rapid rotation. As this results the arm 8 is likewise rotated due to the engagement of said arm with the disc's pin 10.

It is now to be especially noted that, as has been set out previously, the outer free end of said arm 8 lies at a lower position, when at rest, than does the end thereof engaged upon the stem or screw 7. Due, now to the rapid rotation of the arm with the disc 5 the heavy outer or free end of the former in being acted upon by centrifugal force will be lifted, the arm tending to straighten out and takes up a plane of rotation at right angles to the axis of rotation. As this occurs it is clear that as the parts are arranged according to the drawings the said free end of the arm during rotation will strike with considerable force the extremity of the arm 1 above the notch 12. The blow thus delivered brings about two results. First, the sprinkler body is advanced on its mounting a distance commensurate with shock imparted thereto thereby moving the nozzle 3 to a new sprinkling position. Second, the arm 8 having delivered its blow and having thus lost its momentum now falls by gravity to momentarily rest upon the disc, the latter, after the instance of faltering occasioned by the named action again whirling said arm for another impact and a succeeding slight advancement of the sprinkler. Continued action will thus move the sprinkler in the short step-by-step actions throughout its entire revolution.

While the mechanism is shown mounted upon the top of the sprinkler body a somewhat similar arrangement may be housed below the said body within an enclosed shell through which water under pressure may flow, such a form being illustrated in Figures 4 to 8. In Figure 4 a shell portion 14 is mounted upon a supply pipe 15 by screw threads, for example, water from said pipe entering said shell, and for the purpose of imparting a circular swirling movement to the water within the shell a plug 16 may be secured in the threaded portion of the shell where it screws upon the pipe. This plug at several places at or near its periphery is furnished with slits 17, Figure 8, inclined at an angle to the axis of the bore of the pipe 15, the outlets of the slits being directed toward the walls of the shell within which the water is delivered, the purpose of which will appear later.

The described shell 14 is open at its top and receives upon it by screw threads, for example, a closure or cap 18 having a central bore 19, said cap preferably having a central depending extension 20 through which the bore opens, and serving as a bearing for a sleeve 21 rotatable therein.

Fixed upon the upper or outer end the sleeve is the body 22 of a sprinkler provided with a nozzle or nozzles 23, while at the lower or inner end the sleeve is an angular flange 24, a packing

ring 25 lying between the flange and the end of said central extension 20 whereby water cannot escape from the otherwise completely closed shell structure. This structure as may be seen permits rotation of the body 22 and the said sleeve relative to the shell 14-18.

In addition to its make-up the sleeve 21 carries, outward from the bore thereof, a downwardly directed extension, finger, or arm 21'.

In this instance a tube 20' depends from the body 22 centrally of the bore of the sleeve 20 forming a bearing for a shaft 26. Secured on the shaft within the shell 14 is a crossarm 27 having at one end depending spaced fingers 28, Figures 5 and 7, while at the other end the cross arm has one or more vanes 29, the whole being balanced according to recognized practice after mounting thereon a vertically swinging arm 30. This arm at one end is in the present case upturned and extends through a hole 31 in the crossarm at that end having the mentioned vanes 29 and having a head 30' thereon to maintain position in said hole while permitting free vertical play of such arm but limiting the downward movement thereof of the other end of the latter which is free and of some little weight, this said end being retained between the fingers 28 though free to rise and fall. It is seen that the overall length of the crossarm is such that such member is free to rotate with its shaft 26 without striking the depending finger or arm 21' of the sleeve 21. It is observed, however, that the length of the arm 30 is such that it extends to a position where at times it will engage the said finger or arm 21'.

In operation the water entering the shell 14-18 35 in its swirling motion set up by the inclination of the slits 17, acting each as a nozzle, the crossarm is rotated since the vanes 29 at one end thereof and the fingers 28 and lever 30 at the other end are carried along in the flow, the water, 40 of course, finally passing up through the sleeve 21 to and through the nozzles 23, the pressure within the shell fitting the cross arm and preventing dragging of its fingers 28 on the shell-floor beneath.

At a given low rate of rotation of the crossarm that member would not strike the arm or finger 21' of the sleeve but at ordinary water pressure for sprinkling purposes the rotation would be such that, as in the device first described herein, 50 the said crossarm due to momentum will seek a plane of rotation shown in broken lines and thereby engage the finger on arm 21' and in delivering a smart blow thereon impart to it and the sprinkler body a movement forward in rotation according to the force of the blow delivered.

Again, as in the said first described form, after delivering the blow the arm 30 will descend by gravity and pass by the arm 21' but again striking it in the next rotation of the crossarm for a succeeding advancement of sprinkler movement.

In Figure 2a it is noted that the side surface of that portion of the arm 1' against which the arm 8 strikes is inclined at an angle to the perpendicular as at 12. This may be preferred since the said arm 8 upon striking the surface thus inclined will more readily and quickly drop free after striking its blow.

While the device herein described is constructed in a manner to produce the desired result it is to be understood that there are other ways of constructing such device while still lying within the spirit of the invention and the scope of the claims.

I claim:

1. In a sprinkler of the nature and for the pur- 75

- pose described, a sprinkler body mounted to rotate including a nozzle, a member mounted to rotate by impact thereon of a water stream from said nozzle, an arm mounted to be rotated 5 through the instrumentality of said rotatable member, said arm being movable in a plane other than its plane of rotation, and in both its rotational movement and its movement adapted to strike a part of said body to thereby impart thereto a slight rotational movement, said arm being pivoted on a part of the structure of the 10 sprinkler and having a free end.
2. In a sprinkler of the nature and for the purpose described, a sprinkler body mounted to rotate and supplied with water under pressure, and including a nozzle, a member mounted on the body rotated by a water stream issuing from said nozzle, an arm mounted on the rotatable member to rotate therewith and having a free end adapted 15 to swing in a different plane from that of its rotation, said arm in rotation adapted to strike a part of the sprinkler body to impart a slight rotative movement to the latter on its mounting, said arm having, upon its impact with such part a momentary cessation of rotation thereof to free 20 itself from said part and continue its rotative movement.
3. In a sprinkler of the nature and for the purpose described, a sprinkler body mounted to rotate and supplied with water under pressure, and including a nozzle, a member rotatably mounted on the body in position to receive a water stream from said nozzle to cause the same to rotate, an arm carried by and positively driven by said 25 member, said arm being pivotally mounted and free at one end to move in a plane at right angles to its rotary motion with the member, a part on the sprinkler body normally in the path of the rotating arm to receive a blow imparted by the latter, said arm in a momentary cessation of rotation taking up another position freeing itself 30 from said part to continue its forced rotation with said member.
4. In a sprinkler of the type and for the purpose described, a sprinkler body mounted to rotate and connected with a source of water pressure, and including an outlet for such water pressure, a member mounted on the structure adapted to be rotated by water from said outlet, an arm 35 pivotally mounted substantially at the center of rotation of the member positively rotated by the latter, and having a free end adapted to freely move in a plane substantially at right angles to the plane of rotation of said member, the pivot of said arm and the free end of the same normally lying in different spaced planes paralleling the said plane of rotation, said free end of the arm due to momentum during rotation moving into the plane of pivot rotation, a part of the said sprinkler 40 body lying in the path of the said free end and struck thereby when the latter moves into the last named plane, said body being thereby urged a step in rotation on its mounting.
5. In a sprinkler of the type and for the purpose described, a sprinkler body mounted to rotate and connected with a source of water pressure, and including an outlet for such water pressure, a member rotatably mounted on the structure, an arm pivotally mounted at one end at substantially the center of rotation of the member and having a free end normally resting upon the same and positively rotated by it, said free end lying below the pivoted end of said arm and free 50 to swing in a plane substantially at right angles to the plane of rotation, the same adapted in one 55 position of its swing to strike part of said sprinkler body to advance the latter in its direction or rotation on its mounting, said arm in another position freely passing said part.
6. In a sprinkler of the type and for the purpose described, a closed cavited housing connected with a source of water supply, a cavited sprinkler body rotatably mounted on and above said housing receiving water from the latter, said body having an arm fixed with respect thereto and extending into the housing, a rotatable crossarm within the housing having its axis of rotation substantially coincident with the axis of rotation of the body, and an arm pivoted on said crossarm adapted to swing substantially at right angles to the plane of rotation of the latter, and in one position of its swing at slow rotation passing freely by the said arm of the body, and adapted at high rotation to be carried by momentum into sharp abutment with such body-arm to impel 20 it and the sprinkler body in the direction and rotation.
7. In a sprinkler of the type and for the purpose described, a closed housing connected with a source of water pressure and having an inlet 25 fashioned to set up a circular whirling motion of water entering the same, a hollow sprinkler body rotatable above the housing, its bore communicating with the cavity of the latter, said body having an arm fixed with respect thereto and 30 depending within the housing and offset from the center of body rotation, a rotatable cross arm within the housing having its axis substantially coincident with that of the body and an arm pivoted on the crossarm having a free end 35 adapted to move in a direction at right angles to the rotation of the former and in one position of that movement adapted to strike the said arm of the sprinkler body during rotation, and in another position to freely pass by the body-arm, 40 part of the described operating structure including a portion depending into the whirling flow of water to cause rotation of the crossarm by contact of said flow with such position.
8. In a sprinkler of the type named, a sprinkler 45 body connected with a source of water supply and rotatable in a substantially horizontal plane, a positively driven rotatable member at the center of rotation of the said body, an arm pivotally mounted on the member free to rise and fall with respect thereto and positively rotated thereby, said arm having a free end normally lying lower than the position of its pivoted end and in that position being unrestricted in 50 rotative action during slow rotation with the member, and said free end at high rotation with the latter adapted by centrifugal force to lift and swing about the pivoted end of said arm in substantially the same plane therewith, said body having an extension distant from the center of 55 body rotation lying in the path of movement of said free end of the arm at high rotation of the same.
9. A sprinkler of the type named including in its construction a sprinkler body rotatable in a 60 horizontal plane upon a support, a driven structure including an arm pivoted thereon, adapted to be rotated at high speed adjacent said body, said arm being driven by the structure but free to move in a plane at right angles to the plane of 65 rotating motion thereof, said arm having a free end normally lying in a different plane from the pivoted end thereof during slow rates of rotation and adapted at higher rates of rotation to rotate 70 in a different plane and in substantially the same 75

plane with said pivoted end, said body having an extension to receive a blow from said free end at such higher rate of rotation thereof.

10. In a sprinkler of the nature and for the purpose described, a sprinkler body mounted to rotate and supplied with water under pressure, and including a nozzle, a member mounted on the body rotated by a water stream issuing from said nozzle, an arm mounted on the rotatable member to rotate therewith and having a free end adapted to swing in a different plane from

that of its rotation, said arm in rotation adapted to strike a part of the sprinkler body to impart a slight rotative movement to the latter on its mounting, said arm having upon its impact with such part, a momentary cessation of rotation thereon to free itself from said part and continue its rotative movement, the surface of said part receiving the blow being inclined at an angle to the plane of rotation of the device.

10

GUADALUPE BUELNA.
